PROCESS OF PRODUCING CINEMATO-
GRAPHIC THREE- AND MULTI-COLOR
PICTURES

Gerd Heymer, Dessau-Ziebigk, Germany, assignor to Agfa Ansco Corporation, Binghamton, N. Y., a corporation of New York

Application April 13, 1932, Serial No. 605,030
In Germany April 15, 1931

2 Claims. (Cl. 88—16.4)

My present invention relates to a process of producing three- and four-color pictures.

One of its objects provides a process of obtaining three- and multi-color pictures by a combination of the additive and subtractive method. 5 Further objects will be apparent from the detailed specification following hereafter.

Most colored cinematographic pictures are produced according to the additive or subtractive two-color process. In the additive processes the light emanating from the object is divided by means of a suitable system so as to produce side by side two corresponding pictures which, for reproduction, are projected on the screen in coincidence but in complementary colors. In the subtractive processes two partial pictures are arranged in coincidence on the two sides of a film coated on each side with a light-sensitive layer, then printed and dyed in complementary colors. 10 In both cases difficulty is experienced in extending the process to the production of three-color pictures. In the additive process the addition of a third partial picture involves a reduction of the size of the picture, a considerable enlargement 15 of the optical system and a diminution of brightness, while in the subtractive process the arrangement of three superimposed layers causes a great lack of definition in projection and difficulties in the development of the third emulsion layer intercalated between the support and another emulsion layer.

According to this invention by a combination of the additive and subtractive processes, there can be produced in a simple manner films or plates adapted for the production of satisfactory three-color or four-color pictures by simultaneous projection of the several component partial color pictures. In the following I describe the method when applied to the manufacture of three-color pictures. The light emanating from the object is divided, by means of one of the known light-dividing systems, into two bundles of light rays, and in the path of one bundle of rays there is inserted a color-filter which transmits one of the three component colors, while in the path of the other bundle there is placed a filter which transmits the remaining two of the three component colors. The bundles of rays passing through the filters are caused to fall on two emulsion layers sensitized for different colors and arranged one behind the other in the form of a bi-pack. The negatives produced are printed in known manner on a film coated on each side with an emulsion layer. The positives 55 of the negatives produced behind the color filter

which has the greater permeability are dyed or toned according to one of the usual methods, each in the color complementary to the color sensation recorded on the corresponding negative; whereas the positive of the negative produced behind the color filter which is permeable only to one of the three component colors is protected from the action of the treating liquids in a suitable manner by means of a mask or by applying to it a temporary protective layer. The 10 finished positive film is projected by the same optical system and filters as those used for taking the negative.

The following example illustrates the invention as applied to the production of three-color pictures, reference being made to the accompanying drawing in which:

Fig. 1 represents the arrangement for taking a negative.

Fig. 2 the arrangement for projecting the 20 printed positive,

Fig. 3 a front view,

Fig. 4 a cross section of a bi-pack film as used in my process, and Fig. 5 a cross section of another bi-pack film suitable for my invention.

As shown in Fig. 1, the light rays emanating from the object enter a light dividing system constructed in such a manner that the light rays are divided in two bundles. In the paths of the two bundles emerging from the light dividing 30 system there are inserted respectively a minus-flue filter and a blue filter. After passage through the filter the light rays fall on the bi-pack film and produce therein the different color sensations as shown in Fig. 1, the red component 35 being produced behind the green component, and the area of the second emulsion layer positioned behind the area which contains the blue component remaining unexposed. The negatives thus obtained are preferably printed on a film 40 coated on each face with an emulsion layer. In this case the green and the blue component are printed side by side onto the one face and the red component is printed onto the other face in such manner that the developed picture coincides with that of the green component. The area behind the blue component is left unexposed. 45 After development, the positive of the green component is dyed purple and the positive of the red component is dyed bluish green, care being taken when dyeing the positives of the green and the red components that the black and white positive of the blue component remains undyed. The finished film is projected by means of the same light dividing system and filters used in 55

taking the pictures, the filters being arranged in the paths of the corresponding bundles of light, as shown in Fig. 2. The film on which the negatives are produced is arranged in the form of a usual bi-pack as illustrated in Figs. 3 and 4, and may be of normal size. Two pictures are produced side by side in the manner illustrated in Fig. 3. As shown in Fig. 4 the two emulsion layers of the bi-pack are in contact; the emulsion layer in which the green and blue components are produced is sensitive to blue and green and the emulsion layer in which the red component is produced is sensitive to red. The latter layer may either be dyed yellow and sensitized to red as shown in Fig. 4 or it may be provided, in the process of its manufacture, with a red filter by pouring in which case a panchromatic emulsion may be used for the second layer, as shown in Fig. 5.

20 The process, in the first place, is intended more specially for the production of cinematographic color pictures on films. It is, however, likewise suited for purposes of color photography, the emulsion in this case being, if required, supported on glass plates.

25 What I claim is:

1. A process for producing three-color pictures, which comprises dividing the rays of light emanating from the object into two bundles by means 30 of a light-dividing system, arranging in the path of one bundle a color filter permeable to one of the three component colors and in the path of the other bundle a color filter permeable to the remaining of the three component colors, causing 35 the bundle of rays transmitted by the filters to fall on two emulsion layers of suitable color-sensitivity arranged one behind the other in the form of a bi-pack, so that the two color com-

ponents are recorded side by side in one emulsion layer and a third color component is recorded in the second layer in coincidence with one of the color components in the first named layer, developing the exposed emulsion layers, 5 printing the negatives and dyeing or toning the two coincident positives each in the color complementary to the color component recorded on the corresponding negative, and projecting the film through the same optical system and filters 10 as those used for recording the object, whereby 15 a picture in color results.

2. A process for producing three color pictures, which comprises dividing the rays of light emanating from the object into two bundles by means 15 of a light-dividing system, arranging in the path of one bundle a blue color filter and in the path of the other bundle a minus-blue color filter, causing the bundle of rays transmitted by the filters to fall on two emulsion layers arranged one 20 behind the other in the form of a bi-pack and sensitive to green and blue and to red respectively so that the green and blue components are recorded side by side in one emulsion layer and the red component is recorded in the other emulsion layer in coincidence with the green component, developing the exposed emulsion layers, 25 printing the negatives on a film coated on both sides with a light-sensitive emulsion layer, in such a manner that the positives of the green 30 and red components are in coincidence, dyeing the positive of the green component purple, and that of the red component bluish-green, while leaving that of the blue component undyed, and projecting the film through the same optical 35 system and filters as those used in recording the object, whereby a picture in colors results.
